UNITED STATES PATENT OFFICE.

CLEMENTE TORRES, OF RIDGEFIELD PARK, NEW JERSEY, ASSIGNOR OF ONE-HALF TO
JACOB E. MAVUS, OF RIDGEFIELD PARK, NEW JERSEY.

HEATING DEVICE FOR CARBURETERS.

1,367,789.

Specification of Letters Patent.

Patented Feb. 8, 1921.

Application filed September 1, 1920. Serial No. 407,393.

To all whom it may concern:

Be it known that I, CLEMENTE TORRES, citizen of the United States, and resident of Ridgefield Park, in the county of Bergen and State of New Jersey, have invented certain new and useful Heating Devices for Carbureters, of which the following is a specification.

My invention relates to improvements in heating devices for carbureters and the like for use in internal combustion engines and the object of my invention is to provide a device for pre-heating the gases before their introduction into the combustion chamber.

I accomplish this object by the device illustrated in the accompanying drawings in which—

Figure 1 is a sectional view of the device.

Fig. 2 is a cross section of the device on the line 2—2 in Fig. 1.

Similar characters refer to similar parts throughout the several views.

My invention is adapted for use in connection with any desired type of internal combustion engine and as the construction of engines of this character is well known the application and operation of my device will be fully understood without a description of the details of the adjacent parts of the engine.

It is desirable that the liquid fuel supplied to the engine be well vaporized and in proper condition to mix with the air drawn into the mixing chamber and the proper vaporization and mixture or diffusion of vapor and air may be advantageously and effectively attained by the pre-heating of the mixture.

My improved heating device is adapted to be applied between the manifold of an internal combustion engine and the combustion chamber, not shown, of an internal combustion engine and comprises a gasket 1 secured in position between the pipe sections 2 and 3 by means of bolts 4, 5. This gasket 1 is provided with a central gas aperture 6 in which is provided a suitable electrical resistance coil 7 to which is supplied an electrical current from any desired source of supply in the usual manner. Upon the gasket 1 I provide an open cone 8 on which

I mount a supplementary open cone 9 carrying a heating coil 10 to which the electrical current is supplied from any desired source. The cone 9 is provided with inner and outer 55 facings 9¹ and 9² of mica or like insulating material.

In the gasket 1 I provide a loose packing 11 of mineral wool or like material held in position by means of an inner and outer 60 grating 12 and 13 respectively.

The electrical terminals 15 and 16 are connected with the frame and battery respectively in the usual well known manner.

My device being thus assembled, the gas 65 mixture from the manifold of the engine will be conducted through the pipe 2 to my improved heating device. I prefer to use in the gasket 1 a loose packing 11 of mineral wool for the purpose of slightly retarding 70 the gas in contact with the heated surface produced by the heating coil 7 but this packing 11 may be omitted without departing from my invention. The gas mixture thus preferably heated in the gasket 1 passes 75 through the gasket into the heating cone 9 which is heated by means of its resistance coil 10 and the gas mixture is heated by contact with the heated surface and the high temperature of the heating coils before in- 80 troduction into the combustion chamber, whereby the efficiency of the engine will be greatly increased.

Having thus described my invention, what I claim is:

1. In a device of the character described, the combination of a pipe for the combustion gases, an open gasket therein, a loose packing in the gasket to retard the gases and a heating coil in the gasket whereby the 90 gases passing through the gasket are heated before their introduction into the combustion chamber.

2. In a device of the character described the combination of a pipe for the combustion gases, a gasket therein, a heating coil in the gasket and an open cone adjacent the gasket and a heating coil in the cone.

3. In a device of the character described, the combination of a pipe for the combustion gases, a gasket in the pipe, a heating coil in the gasket, an open cone mounted on

the gasket, a heating cone carried thereby and having an inner and outer facing of insulating material.

4. In a device of the character described, 5 the combination of a pipe for combustion gases, an open gasket in the pipe, an inner and an outer grating on the gasket, a loose

packing between said gratings to retard the gases, an open cone adjacent the gasket and a heating coil in said cone.

Signed at Ridgefield Park in the county of Bergen and State of New Jersey this 24 day of August, A. D. 1920.

CLEMENTE TORRES.
